UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON HEELS.

1,161,058.

specification of Letters Patent. Patented Nov. 23, 1915.

Application filed November 27, 1911, Serial No. 662,601. Renewed March 4, 1915. Serial No. 12,108.

To all whom it may concern:

Be it known that I, THOMAS LUND, a citizen of the United States, residing at Beverly, in the county of Essex and State of Massachusetts, have invented certain Improvements in Machines for Operating on Heels, of which the following description, in connection with the accompanying drawings, is a specification, like reference characters on the drawings indicating like parts in the several figures.

This invention relates to improvements in machines for operating on heels and is herein described as embodied in a heel pricking machine.

An object of the invention is to simplify the construction of pricking machines and improve their operation upon heels which it is desired to attach by nails driven at an inclination to the tread face and which accordingly must be pricked obliquely. Heretofore it has been customary to hold a heel blank between two heel-engaging members the effective faces of which are disposed at an inclination to the path of the awls. It has been found desirable to shape the inclined faces of both the heel holding members to coincide in their inclination with the tread and heel seat surfaces of the heel to be operated upon. The face of the member against which the heel is forced during the working stroke of the awls must be properly shaped to hold the heel against slipping or tilting during this operation as otherwise the awl holes will take a wrong direction, and the face of the die plate through which the awls reciprocate must also be shaped properly to prevent movement of the heel during the stripping or withdrawal of the awls as otherwise the awls will be bent and are likely to be broken or the lifts of the heel pulled apart. Moreover, if a fair bearing is not afforded for both surfaces of the heel when it is subjected to pressure preliminarily to the pricking operation, as is customary, the heel is likely to be distorted. Heretofore the desired shape has been given to the die plate by grinding off on a bevel its effective work-engaging face. By this expedient satisfactory operation is secured in dealing with heels having a given shape but if it is desired to operate upon heels of a different shape, or to vary the inclination of the awl holes in the heel

it is necessary to substitute a new die plate having its face ground to a correspondingly different bevel.

With these considerations in view an important feature of the present invention, consists in providing an auxiliary heel-engaging stop or abutment movable into and out of operative position between the work-engaging face of the die plate and the proximate surface of the heel blank and constructed and arranged, when in operative position, to hold the heel at an inclination to the face of the die plate and the awl passages therein.

Another important feature of the invention consists in so arranging a stop for engaging one face of the heel as to extend from the member which bears upon the opposite face of the heel, for example, as by mounting the stop for the tread face of the heel upon the member which carries the heel seat plate. An advantage of this construction is that the heel blank may be thereby more positively handled and moved to and from operative position than in machines where the heel blanks are manipulated entirely by hand. The heel is also held more firmly while it is being stripped from the awls.

As herein shown the stop is moved automatically into and out of operative position and accordingly a stop arranged for automatic operation in this manner constitutes another important feature of the invention.

In presenting a heel blank to the die plate with its proximate face inclined thereto it will be apparent that the awl guiding passages in the die plate terminate short of the surface of the heel and that, while traversing the space between the die plate and the heel, the awls will be unsupported. Another feature of the present invention consists in providing means for supporting and guiding the awls or tools in this space regardless of the shape of the heel or the inclination of its proximate surface relatively to the face of the die plate. As herein shown this result is effected by providing the tools, or certain of them, with yielding guiding tubes which are arranged to be moved automatically into conformity with the surface of the heel by the presentation thereto of the heel. The provision of guiding tubes of this character constitutes another important

feature of the invention. It is, further, believed that guiding tubes of this character have never before been used in combination with a stop for holding the work in an inclined position and this combination broadly constitutes still another feature of the invention.

For purposes of illustration the invention will now be described as embodied in a pricking machine substantially of the type disclosed in Letters Patent of the United State No. 1,077,929, granted November 4, 1913, upon an invention of John E. Glidden, although the present invention is not limited to that type of machine but has a more general application.

In the drawings,—Figure 1 is a view in side elevation of the operating parts of a pricking machine showing a heel blank in which the awls are inserted, and Fig. 2 is a similar view showing the parts of the machine in their initial position.

The machine herein shown, like that of said patent, comprises a head 10 in which is removably received the follower plate 12 having a curved and inclined face shaped to fit the heel seat surface of the heel blank 50 standing with its breast surface inclined slightly to the horizontal. Oppositely disposed with respect to the follower plate 12 is the perforated die plate 14 having a substantially vertical engaging face and horizontal awl passages in which work the awls 16 set in the awl plate 18. The heel blank 50 rests upon a bottom plate 20 which extends outwardly toward the front of the machine thus affording a convenient support upon which successive heel blanks may be presented in operative position.

The heel blank is positioned laterally by a forked yoke 22 arranged to reciprocate vertically adjacent to the face of the die plate. Means, not shown, are provided for advancing the follower plate 12 to engage the heel blank 50 between itself and the die plate 14, the arrangement being such that after the heel has been engaged relative movement of the awls and die plate takes place whereby the awls are forced into the heel blank. The means for advancing the head 10 and for causing relative movement of the die plate and awls are not illustrated herein as they form no part of the present invention. They are, however, fully illustrated and described in the patent above identified to which reference may be had for details of construction.

In order to hold the heel blank inclined with respect to the die plate 14 and the awls 16 the hook shaped stop 30 is arranged to engage the rear portion of the tread surface of the heel and hold it away from the surface of the die plate. The stop 30 is adjustably mounted upon one end of the lever 32 pivoted on the pin 33 to ears extending

upwardly from the bracket 34 on the head 10. Normally the stop 30 is held in an elevated position by a spring 36 which bears upon the lever 32 at the rear of its pivot and acts against the overhanging arm 38 on the bracket 34. In this position the stop does not interfere with the presentation of a heel blank to the machine by moving the blank laterally upon the bottom plate 20 into alignment with and between the die plate 14 and the head 10.

Any convenient means may be employed for moving the stop 30 positively into operative position and for holding the stop during the pricking and stripping operations. As shown herein the lever 32 is provided at its rear end with a roller 39 which runs upon a stationary cam track 40. The cam track 40 is so shaped as to elevate the rear end of the lever 32 when the head 10 is moved toward the die plate and accordingly the stop 30 is depressed into substantially the position shown in Fig. 1 and held positively in this position during the pricking operation and until the stripping operation has been completed.

In order to guide the awls while they traverse the space between the engaging face 15 of the die plate 14 and the tread surface of the heel blank 50, the die plate is chambered to receive the guiding tubes 44 which are normally held yieldingly in the position shown in Fig. 2, that is, with their outer ends in a plane parallel to the face 15, by compression springs 46 one of which encircles the rear portion of each tube. It will be seen therefore, that when a heel held with its face at an inclination to the die plate is forced against the ends of the tubes 44 the lower tubes will be forced back into their chambers for substantially their entire length while the remaining tubes automatically adjust themselves to engage the inclined face of the heel blank at the points where the latter is to be operated upon by the awls.

In operating the machine a follower plate 12 having the desired shape is fitted into the head 10, a heel blank is placed in position and the machine is started. Thereupon the head 10 advances toward the die plate engaging the heel blank and forcing it against the ends of the tubes 44. The action of the inclined face of the follower plate 12 in pressing the heel blank against the ends of the yielding tubes causes the heel blank to tilt until its heel seat face engages the follower plate fairly as shown in Fig. 1 and at the same time the cam 40 acts to move the stop 30 into engagement with the tread face 125 of the heel blank. The pricking operation is then effected either by forcing the awls through the die plate or by moving the die plate, heel blank and head relatively to the awl block. When the awls have been in-

serted to the desired depth the head 10 and the die plate are both moved reversely relatively to the awls in the stripping operation, the heel blank is drawn off of the awls being maintained in its inclined position by the action of the stop 30 which prevents the blank from tilting toward the surface of the die plate.

Having thus described my invention what 10 I claim as new and desire to secure by Letters Patent of the United States is:—

1. A machine for operating on heels having, in combination, oppositely disposed heel-engaging members, a gang of tools 15 operating through one of said members, and a heel-engaging device having a portion shaped to engage the tread surface of the heel, said device being mounted upon the other of said members and arranged to hold 20 a heel blank positively against movement in the direction of said tools while the tools are being retracted into said first mentioned member.

2. A machine for operating on heels having, in combination, a plate for engaging a 25 part of the tread surface of a heel blank, an oppositely disposed member shaped to fit the heel seat surface of the heel blank, and a retaining device supported upon said 30 member and arranged to engage the tread surface of the blank.

3. A machine for operating on heels having, in combination, a die plate, awls working 35 therein, a supporting member shaped to hold a heel blank with its tread face at an inclination to said die plate, and a retaining device mounted upon said supporting member and arranged to prevent movement 40 of the heel blank during the retraction of the awls.

4. A machine for operating on heels having, in combination, a die plate having passages therein, a gang of awls arranged for reciprocation through said passages in a 45 direction substantially perpendicular to the face of said die plate, means for supporting a heel blank with its tread face inclined to the path of said awls, and a retaining device connected with said supporting means 50 and arranged to hold the heel blank with its tread face in said inclined position during the retraction of the awls.

5. A machine for operating on heels having, in combination, a die plate and a heel 55 supporting member having relatively inclined faces, and a retaining device mounted upon the latter member and having a portion shaped to engage the tread face of a heel blank, to hold the blank positively 60 against movement away from said member.

6. A machine for operating on heels having, in combination, a die plate and awls working therein, a supporting member arranged to hold a heel blank with its tread 65 face at an inclination to said die plate and

in engagement with the die plate near its breast edge, and a retaining device connected with said supporting member and arranged to engage the heel blank near the rear end of its tread face and prevent angular movement of the blank during the retraction of the awls.

7. A machine for operating on heels having, in combination, a die plate, tools working therein, a supporting member arranged 75 to hold a heel blank with its tread face inclined to said die plate, and a heel blank retaining device mounted on the supporting member and having provision for adjustment to accommodate blanks of different 80 heights.

8. A machine for operating on heels having, in combination, a die plate, tools working therein, a supporting member arranged to hold a heel blank with its tread face inclined to said die plate, and a retaining device for holding one end of the tread face of the heel blank away from said die plate, said retaining device being movable from 85 operative to inoperative position.

9. A machine for operating on heels having, in combination, relatively movable heel-engaging members having oppositely disposed, relatively inclined faces, a retaining device for holding part of one face of a heel 95 away from one of the members, and means for moving said retaining device into heel engaging position when said members are moved toward each other.

10. A machine for operating on heels having, in combination, relatively movable heel-engaging members having oppositely disposed faces relatively inclined, tools for operating on a heel held by said members, a movable retaining device for holding part 105 of one face of a heel away from one of the members, positive means for moving said device into holding position, and yielding means for retracting said device.

11. A machine for operating on heels having, in combination, a die plate having a plurality of tool guiding tubes projecting therefrom arranged for lengthwise yielding movement to accommodate themselves to the surface of work presented to the die plate 115 at an inclination, a stop arranged to hold one edge of the work away from the die plate, and tools working in said tubes in a path inclined to the face of the work.

12. A machine for operating on heels having, in combination, a die plate having a plurality of tool guiding tubes yieldingly mounted therein so that work presented to the die plate with its face at an inclination will force said tubes into such positions 125 that their outer ends will lie in a plane inclined to the face of the die plate, a stop arranged to hold one edge of the work away from the die plate, and a gang of tools working in said die plate.

13. A machine for operating on heels having, in combination, heel engaging members having relatively inclined faces, and a plurality of tubes set in one of said members and held with their ends in a plane parallel to the face of the member in which they are set, the other of said members having means for holding a heel at an angle to the tube-carrying member and being movable to force a heel against the ends of said tubes thereby causing them to move into conformity with the inclined surface of the heel by which they are engaged.

14. A machine for operating on heels having, in combination, relatively movable awls and die plate, said die plate having a work-

engaging face and awl passages extending at right angles thereto, a retaining member arranged to hold the tread surface of the heel at an inclination to said work-engaging face of the die plate, movable guiding tubes arranged to guide the awls in the space between said die plate and the heel, and a pressing member having an oblique face for engaging the heel seat surface of a heel. 20

25 In testimony whereof I have signed my name to this specification in the presence of two subscribing witnesses.
